UNITED STATES PATENT OFFICE.

ALBERT BRUHN, OF ST. BONIFACIUS, MINNESOTA.

SNAP-HOOK.

1,332,884.

Specification of Letters Patent.

Patented Mar. 9, 1920.

Application filed July 25, 1919. Serial No. 313,266.

To all whom it may concern:

Be it known that I, ALBERT BRUHN, a citizen of the United States, residing at St. Bonifacius, in the county of Hennepin and State of Minnesota, have invented certain new and useful Improvements in Snap-Hooks; and I do hereby declare the following to be a full, clear, and exact description of the invention, such as will enable others skilled in the art to which it appertains to make and use the same.

My invention relates to improvements in snap-hooks and has for its object to provide such a hook as will release the members which it connects under excessive strain. The improved snap-hook is intended for general use, but especially adapted to connect the trace carriers of a harness to the hip straps whereby, in case a horse kicks over the traces, the snap-hook will release the connected parts before the harness will break and thus prevent damage to the harness.

To the above end, generally stated, the invention consists of the novel devices and combinations of devices, hereinafter described and defined in the claims.

The invention is illustrated in the accompanying drawings, wherein like characters indicate like parts throughout the several views.

Referring to the drawings:

Figure 1 is a perspective view of the improved snap-hook connecting a strap and ring;

Fig. 2 is an edge elevation of the same;

Fig. 3 is a plan view of the improved snap-hook; and

Fig. 4 is a transverse section taken on the line 4—4 of Fig. 1.

As shown, the improved snap-hook is formed from a single piece of spring wire, intermediately folded upon itself to form the body 5. One end of the wire is bent to form the tongue 6 which extends from the underside of the body 5, at the rear end thereof, upward between the members of said body and normally and yieldingly rests on the transverse portion of the front end of the body 5. The other end of the wire

is bent to form an attaching loop 7 and after completing said loop is twisted at 8, around both members of the body 5 and the tongue 6 to connect the several members of the improved snap-hook. While the attaching loop 7 is shown as of rectangular form, it may of course, be made in various different shapes.

Both members of the body 5 are bent downward to afford a transverse ring seat 9, that is oblique to the line of pull and over which ring seat the tongue 6 extends. As shown, a strap Y is attached to the loop 7 and a ring Z rests in the ring seat 9 and is yieldingly held therein by the tongue 6. Obviously, an excessive pull on the ring Z will cause said ring to be cammed out of the oblique ring seat 9 against the tension of the tongue 6 and thereby release said ring from the snap-hook.

What I claim is:

1. A snap-hook arranged to release by a longitudinal pull under excessive strain and return to normal position.

2. A snap-hook having a ring seat, and a tongue extending over said ring seat and arranged to release by a longitudinal pull under excessive strain and return to normal position.

3. A snap-hook having a ring seat that is oblique to the line of pull, and a tongue extending over said ring seat and arranged to release by a longitudinal pull under excessive strain and return to normal position.

4. A snap-hook formed from a single piece of spring wire that is intermediately bent upon itself to afford a body, one end of said wire being bent to form a tongue normally and yieldingly overlying the outer face of the transverse portion of the front end of said body, the other end of said wire being bent to form a retaining loop and thereafter bent around the members of said body and tongue to connect the several parts of the snap-hook.

5. A snap-hook formed from a single piece of spring wire that is intermediately bent upon itself to afford a body, the members of said body being downwardly bent to

afford a ring seat that is oblique to the line of pull, one end of said wire being bent to form a tongue normally and yieldingly overlying the outer face of the transverse portion of the front end of said body and extending over the ring seat, the other end of said wire being bent to form a retaining loop and thereafter bent around the members of

said body and tongue to connect the several parts of the snap-hook. ¹⁰

In testimony whereof I affix my signature in presence of two witnesses.

ALBERT BRUHN.
